UNITED STATES PATENT OFFICE.

CHARLES A. JOHNSON, OF SUPERIOR, WISCONSIN.

GRAIN DOOR.

Application filed April 26, 1923. Serial No. 634,770.

To all whom it may concern:

Be it known that I, CHARLES A. JOHNSON, a citizen of the United States, residing at Superior, in the county of Douglas and 5 State of Wisconsin, have invented certain new and useful Improvements in Grain Doors, of which the following is a specification.

My invention relates to grain doors particularly adapted for railway grain cars and 10 the object is to provide a door of such construction that a grain car or grain bin in which it is installed may be rapidly and conveniently filled or emptied with no waste 15 of effort or materials and the door when not in use may be put away in the smallest possible space in the car in readiness to be used again.

In the accompanying drawing:

20 Fig. 1 is an interior side elevation of one side of a grain car equipped with my improved grain door.

Fig. 2 is a vertical section on line 2—2 in Fig. 1.

25 Fig. 3 is a section on line 3—3 in Fig. 1, but showing the door of my device in raised position.

Fig. 4 is an outside elevation of a side of 30 a car having a door opening equipped with my improved grain door.

Fig. 5 is a section on line 5—5 in Fig. 1.

Fig. 6 is a modification of a small portion of Fig. 2.

Fig. 7 is Fig. 6 further modified.

35 Referring to the drawing by reference numerals, 10 designates the floor and 11 one of the sides or side walls and 12 the roof of a grain car having a door opening 13 which is usually closed by a slidable outer door (not shown). The inner side of the 40 door opening has its lower and larger portion closed by my horizontally sliding door 14, which is preferably made of sheet metal, reinforced by horizontal ribs 15, 15^a, 15^b and two vertical ribs 16, the latter forming 45 the vertical edges of the door and giving the outer side of it a cavity the top of which is closed by the rib 15, and ribs 16 extend as legs 16^a below the cavity and forming 50 with the bottom edge of the middle portion of the door a grain outlet gap 16^b. The door is provided with two hangers 17 having grooved rollers 18 riding on a rail 19 secured at 20 above the door opening and 55 extending as 19^a beyond the opening to enable the door to be slid when idle into a

pocket 21 which is formed between the side wall 11 of the car and a second wall 22—23 secured on uprights 24 and being high enough for the loaded grain to never reach 60 above it. The edge of the pocket 21 nearest the door opening 13 is normally closed by a narrow door or closure 25 hinged at 26 and having a pivoted catch 27 swingable into a cavity 28 in the wall 11 when the pocket 65 is closed so no grain can get into it.

The rail 19—19^a is offset downwardly to form shoulders 29—30—31 which tend to hold the rollers 18 in place and thereby the door 14 in place on the rail when it is 70 either idle in the pocket or closing the opening 13, in either of which positions the door 14 may have its legs 16^a close to the car floor, and raised therefrom during 75 transition only, when the door is forced from the one position to the other and thereby is raised on the inclines 29—30 and 31.

The door 14, when closed, projects partly upon the wall or door frame at both sides of the door opening so as to resist pressure 80 of grain loaded in the car. The space or opening between the legs 16^a (see Fig. 1) is normally closed by a vertically movable door section or plate 32 (see lower part of Fig. 2). Said plate has its upper edge 85 formed as a hook or channel 33 arranged to straddle and rest upon the top edge of the rib 15^a when the plate is raised to let out grain, or upon the edge of rib 15^b when the plate is closed or in its lowered position. 90

The plate is slightly wider than the door opening 13 so as to bear with vertical edges against the walls 11; hence, when the plate is in the lower position it is locked against accidental raising by a spring catch 34 which 95 may engage the very top curve of the plate, as 34^a in Fig. 6, or a lip 35 formed at the edge of the curved portion of a longer spring catch 34^b as in Fig. 7; and when the plate is in the upper position the same catch 100 or spring arm 34 presses it against the inner side of hook 15^b (as in Fig. 3) and thereby holds the plate frictionally in the hooks 15^a and 15^b against upward movement until the operator takes hold of the handles 36 (best shown in Fig. 4) and changes the 105 plate from one position to another. The cleat 37 fixed on the plate is for a crow-bar to get hold of in starting the plate upward when grain is resting against its inner side. 110

In the operation, when the car is to be loaded with grain or similar goods, the open-

ing 13 is partly closed by the door 14, the latter having its plate 32 lowered and locked by the catches 34; and the pocket is closed by the door 25. The grain is then poured in above the door 32 until the car is loaded, and the outer car door (not shown) may be closed and sealed.

When the grain is to be unloaded the plate 32 is raised and the grain run out through the opening originally closed by the plate. After the grain gets so low in the car that it will not run out in said manner, the door 25 is opened, door 32 pushed into the pocket 21 and door 25 closed, whereupon the rest of the grain is removed from the car through the main door opening by any suitable means.

The grain door 14 may remain in the pocket until it is to be used again.

Having thus described my invention what I claim is:—

1. The combination with a box car having a door opening in its side and along the inner side of the wall, a pocket open at the top and at the edge nearest to the door opening, and a horizontal track secured above said door opening and pocket, of a main door having hangers with rollers riding on the track, and means for stopping the door in the pocket and in a position to close the

door opening; said pocket having a narrow hinged door arranged to close the inlet for the main door, and means holding said narrow door closed when so desired; the lower end of said main door being provided with a large gap, and having in its outer side a cavity; a plate movable vertically in the cavity and adapted to close the gap, and means on the door to engage the plate to hold it raised and in lowered position; said plate having its upper edge curved toward the door and downward to form an inverted channel, and the lower edge of the door having an upwardly curved rim entering said channel when the plate is down.

2. A grain car having a door opening and a horizontally slideable door for closing the opening, said door having in its lower edge a gap forming a starting outlet for the grain, and above said gap a cavity in the outer side of the door; a plate slideable up and down in the cavity for closing the gap to any desired extent, a leaf spring fixed on the door and pressing on the adjacent side of the plate to hold it frictionally in desired positions and arranged to also engage and hold it firmly in its fully closed position.

In testimony whereof I affix my signature.

CHARLES A. JOHNSON.
